Primary Examiner — John M Otte(74) *Attorney, Agent, or Firm* — Cook Alex Ltd.(57) **CLAIM**

The ornamental design for a controller with a user interface, as shown and described.

DESCRIPTION

The sole FIGURE is a front view of a controller with a user interface flat control panel.

The dashed broken lines showing portions of the user interface flat control panel, text and other elements in the FIGURE form no part of the claimed design. The outer dashed broken line in the FIGURE represents a boundary and forms no part of the claimed design.

1 Claim, 1 Drawing Sheet(56)
